UNITED STATES PATENT OFFICE.

ALBERT D. SMITH, OF DETROIT, MICHIGAN.

ROTARY TAKE-UP FOR SEWING-MACHINES.

1,329,637.

Specification of Letters Patent.

Patented Feb. 3, 1920.

Application filed March 25, 1918. Serial No. 224,475.

To all whom it may concern:

Be it known that I, ALBERT D. SMITH, a citizen of the United States, residing at Detroit, in the county of Wayne and State of Michigan, have invented certain new and useful Improvements in Rotary Take-Ups for Sewing-Machines, of which the following is a specification.

This invention, a division of my Patent No. 1,261,170, dated April 2, 1918, for improvements in sewing machines, relates to a rotary take-up for sewing machines.

The primary object of the invention is to provide an improved rotary take-up by means of which a relatively large slack of upper thread may be produced for passage around a lower thread case or receptacle, and to accurately control the slack thread without danger of tangling and breaking 20 the same, especially when operating at a high speed.

The production of a larger slack of upper thread than required in the ordinary machine is necessitated in this instance by the use of comparatively large lower thread receptacle having a thread capacity considerably greater than is found in prior sewing machines on the market. Thus, by the use 25 of a large lower thread supply, especially in factory sewing, much time and labor is saved that was heretofore necessitated in the frequent rewinding and replacement of bobbins which carried a very limited supply of thread.

Another important object of this invention is to provide a rotary take-up devoid of auxiliary take-up devices, spring and gear actuated thread controls, spring-acting thread 35 detainers and similar parts coöperating with the take-up proper for controlling and detaining the slack thread. Such auxiliary devices, thread checks and detainers are found to be unsatisfactory and impractical, in that they complicate the construction and operation and cause the thread to break and become wound and tangled in the take-up. These undesirable features I have obviated by the provision of a pair of closely positioned rotary plates connected together by 40 but a single eccentric pin disposed relatively close to the periphery of the plates and constituting the sole means within the periphery of the plates for operating on the thread. I have also provided a wall or guard 45 circumscribing the plates and shaped in a peculiar and advantageous manner to properly

guide and control the thread as it enters and leaves the take-up.

A further feature of my improved take-up is to produce the relatively large slack of 60 thread mentioned above by means of a take-up of minimum diameter. This is attained by arranging the thread guides so that the thread will enter and leave the take-up at substantially the same point, or rather in 65 such proximity that the slack produced is equal to substantially twice the diameter of the take-up.

These and other objects will be appreciated as the invention becomes better understood 70 by reference to the following description when considered in connection with the accompanying drawings, in which—

Figure 1 is a face view of a sewing machine head illustrating my improvements in 75 connection therewith;

Fig. 2, a side view thereof;

Fig. 3, a detail in perspective of the rotary take-up casing, detached from the 80 machine;

Fig. 4, a perspective, partly in section, of the take-up disks or plates; and

Fig. 5, a sectional view taken on the line 5—5 of Fig. 3.

My improvements as mentioned above, are particularly adapted for use in connection with a lower thread receptacle of relatively large capacity, such for example, as is illustrated in my patent mentioned above. In 90 order to facilitate a clear understanding of the present invention, I have but briefly indicated in the drawings a lower thread receptacle in connection with a rotary hook such as disclosed in said application. This 95 lower thread receptacle or case 6, stationary in a raceway in the rotary hook structure 7, is adapted to carry any of various sized spools, from small to relatively large size, and to even carry a ball of thread, in which 100 latter case, the thread capacity is many times greater than is possible with any previous machines on the market. As explained in my patent, this lower thread receptacle necessitates the production by a 105 take-up mechanism of a large slack of upper thread in order that this thread may be passed by a lower hook 8 in a loop of the requisite size around the lower thread receptacle. It is with this object in mind and 110 the desire to provide a simple and practical construction which will not break or tangle

the thread, especially when operating at high speed, that the present improvements pertaining to the take-up have been devised.

I have, therefore, illustrated, only such parts of a sewing machine as are necessary for a clear understanding of the present invention. The parts shown consist of a work plate 9, head 11, needle bar 12, presser-bar 13 and driving shaft 14. The open face of 10 the head 11 is closed by a take-up container designated in general by reference character 15 and illustrated in detail in Fig. 3. This container, in the form of a circular plate having a central aperture 16 and a raised 15 peripheral flange or wall 17, is provided at its lower end with a face plate 18 shaped to fit over the lower end of the head 11 and to carry suitable means for guiding the thread 20 to and from the take-up. The container may be detachably secured to the head by any suitable means, such as by screws.

The rotary take-up proper consists of a pair of circular plates or disks 19 and 21 of slightly less diameter than the interior 25 of the flange 17, fixedly secured together by a take-up pin 22 positioned adjacent to the peripheral edge of the plates. The rotary plates, co-axial with the driving shaft 14, are fixedly connected thereto through the 30 agency of a coupling 23 passing through the aperture 16 and connected to the plate 19. The needle-bar crank is not essential in 35 the driving connection, as my improvements contemplate driving the rotary plates by mechanism of any suitable construction. It will be observed that the flange 17 forms a circumferential wall about the thread compartment interposed between and formed by the spaced disks 19 and 21 and that the 40 lower portion of the flange is cut away to form inclined thread guides 24 and 25, noted in Fig. 5, the purpose of which will presently appear.

The upper thread taken from a spool, not 45 shown, suitably mounted on the head of the machine is passed through a suitable tension device and thence enters between the take-up plates from the lower side thereof in the manner indicated in Fig. 1. In the present 50 illustration of my improvements, the thread tension is mounted on the lower extension 18 of the take-up container and consists of spring-pressed tension disks 26 mounted on a post 27 fixed to said plate 18. The upper 55 thread, after passing through the tension 26 is guided by the inclined surface 24 to enter between the rotary take-up plates at the lowermost side thereof, thence passes over and around the pin 22 and leaves the 60 take-up in close proximity to the entrance point of the thread thereto. It will be noted, viewing Fig. 2, that by reason of the lower portion of the flange 17 being cut away, the outer disk 21 of the take-up projects slightly beyond the inner portion of

the inclined edge 24 of said cut-away. This surface 24 guides the thread after it leaves the tension and directs it to the inner side of the outer disk 21 so that the thread will properly enter the take-up. After leaving 70 the take-up, any suitable guide means, such as the members 28, may be provided directly above the needle so that the thread will pass directly to the same. By means of this arrangement, when the take-up pin 22 is carried to the point A indicated in Fig. 1, a slack of upper thread will be drawn equal in length to substantially twice the diameter of the take-up. It will be particularly noted 75 that this relatively large slack of upper 80 thread is produced by a take-up of minimum diameter, including but a single eccentric pin, and that neither auxiliary take-up devices, spring checks, detainers nor extra 85 studs are employed.

At the time the looper or rotary hook 8 takes the upper thread from the needle the take-up pin 22 has reached a position indicated approximately by the dotted line B, and it follows that substantially the full 90 amount of slack produced by the take-up is at this point loosely contained between the take-up disks before being drawn down by the looper. In order to prevent this slack 95 thread from passing out of the take-up by the action of gravity and centrifugal force, to avoid the use of spring detainers, etc., and to allow proper passage of the slack thread from the take-up as the thread is required in forming the lower loop. I have positioned 100 the take-up plates 19 and 21 in such close proximity and have so arranged the peripheral wall 17 and inclined guide surface 25 as to effect a tension or resistance on the out-going thread for controlling the same during this period. There is an instant in the 105 operation of the machine when the full slack of upper thread produced in the take-up is loose therein and seemingly uncontrolled before being drawn down by the rotary 110 take-up. This slack thread as already mentioned, is controlled during this period by the relatively close walls of the disks 19 and 21, peripheral flange 17 and the resistance created by the passage of the out-going 115 thread over the inclined surface 25.

It is believed that the foregoing conveys a clear understanding of my improvements and of the objects prefaced above, and it should be understood that while I have illustrated but a single embodiment, various changes might be made in the construction and arrangement without departing from the spirit and scope of the invention as expressed in the appended claims.

I claim:

1. In a sewing machine, a vertical rotary take-up including a pair of spaced rotary plates, an eccentric thread drawing member connecting said plates, and a wall circum-

- ferentially disposed about said plates and constituting the peripheral wall of the thread chamber, that portion of the wall disposed at the underside of the take-up 5 being cut away on both sides of a vertical plane intersecting the axis of the take-up to form inclined guides, one of which permits entrance of thread to the take-up and the other withdrawal of thread therefrom, said 10 wall coöperating with said plates to cause a tension on the thread in its passage from the take-up.
2. In a sewing machine, the combination of a pair of spaced concentric take-up disks 15 joined and held in rigid relative relation by but a single thread-drawing member disposed near the periphery of the disks and having a circular peripheral thread-engaging surface, means connected concentrically 20 to one of the disks for revolving them about a horizontal axis, means for guiding the thread so that it enters and leaves the space between the disks from the underside thereof whereby the length of thread between the 25 disks at the highest point of the concentric thread-drawing members will be twice the diameter of the take-up, and a wall or flange circumscribing the disks in close proximity to the periphery thereof and having an elongated cutaway at the underside of the disks 30 through which the thread enters and leaves the space between the disks.
3. In a sewing machine, the combination of a sewing machine head having an open 35 end, a take-up container closing said open end and detachably connected to the head and shaped to provide an annular outstanding flange and further shaped to provide a central coupling opening, a pair of disks 40 disposed within said annular flange, a take-up pin joining said disks and holding them in rigid spaced relation, a needle-bar driving shaft concentric with the disks, and means extending through the central open-
- ing in the take-up container and connecting 45 the innermost disk rigidly with the needle-bar driving shaft.
4. In a sewing machine, the combination with a head, a take-up container detachably connected to the head and formed with an 50 annular outstanding flange or wall, a pair of take-up disks disposed within said annular flange and connected by a take-up pin disposed near the periphery of the disks, means for rotating the disks, said annular 55 flange having an elongated cutaway below the disks through which the thread enters and leaves the space between the disks, and thread-guiding means below the peripheral flange for guiding the in and out going 60 thread which passes through said elongated cutaway.
5. In a sewing machine, the combination with a head, a take-up container detachably connected to the head and formed with an 65 annular outstanding flange or wall and with a depending face plate, a pair of take-up disks disposed within said annular flange having an elongated cutaway below the disks through which the thread enters and 70 leaves the space between the disks, and thread-guiding means mounted on said depending face plate and arranged to guide the in and going out thread which passes through said cutaway.
6. In a sewing machine, the combination 75 of a pair of vertical take-up disks arranged in relatively close proximity to form a narrow thread compartment, a single take-up pin joining said disks near the periphery 80 thereof and constituting the only thread operating means in said compartment, and a peripheral retaining wall or flange about the disks in close proximity thereto and having an elongated cutaway at the under- 85 side of the disks through which the thread enters and leaves said thread compartment.

ALBERT D. SMITH.
